UNITED STATES PATENT OFFICE.

ANNA L. PECK, OF MINNEAPOLIS, MINNESOTA.

FOLDABLE BOX.

1,072,643.

Specification of Letters Patent.

Patented Sept. 9, 1913.

Application filed October 7, 1912. Serial No. 724,364.

To all whom it may concern:

Be it known that I, ANNA L. PECK, a citizen of the United States, residing at Minneapolis, in the county of Hennepin and State of Minnesota, have invented certain new and useful Improvements in Foldable Boxes, of which the following is a specification.

This invention relates to that class of foldable boxes having a series of cells designed to hold eggs or other articles separated from one another.

It is the object of the invention to provide a box of the kind stated which is so constructed that it may be collapsed or folded flat for convenience in shipment, and also to provide improved means whereby the box can be readily set up and its parts locked in this position. These objects are attained by a novel combination and arrangement of parts to be hereinafter described and claimed, reference being had to the accompanying drawings, in which—

Figure 1 is a perspective view of the box set up ready for use, with the lid swung open; Fig. 2 is a longitudinal section of the box, and Fig. 3 is a transverse section thereof.

Referring specifically to the drawings, the box is constructed of a piece of card-board or other suitable material which is bent and folded to form a top 10, a side 11, a bottom 12, a side 13, and a lid 14. The top 10, adjacent to the side 13 has a marginal flap 15 which is pasted or otherwise permanently fastened to said side. The bottom has end flaps 16 which, upon being bent up, form the end walls of the box. The top 10 has marginal tongues 17 at its ends which are adapted to be inserted through slits 18 in the free ends of the flaps 16 after said flaps are bent up, whereby the end walls of the box formed by said flaps are locked in set-up position. The slits 18 coincide with the top 10, and the material above the same, together with the projecting ends of the tongue 17, are folded inward over on the top 10, over which folded parts the lid 14 seats when in position to close the box. Suitable

means will be provided for holding the lid 50 closed.

On the top 10 is pasted or otherwise fastened a sheet 19 which is slitted to form a series of rectangular bendable tongues 20 arranged in three rows as shown. The number of rows, and the number of tongues in the rows may, of course, be varied according to the size of the box. The top 10 is also slitted to form rectangular bendable tongues 21, which are located adjacent to 55 the tongues 20 but at a right angle thereto. The length of the tongues 20 and 21 is such, that when they are bent down, they reach the bottom 12 of the box. The tongues after being bent down form the walls of the 60 65 cells.

To the bottom 12, on the inside of the box, is pasted or otherwise secured a sheet 22 having end portions 23 which are free and adapted to be bent up between the 70 tongues 21 alongside the tongues 20 to form partitions between the rows of the cells. If desired, these partitions may be dispensed with, and if they are used, one set of 75 tongues may be left off.

The box and the cell structure herein described fold flat which saves room in storage and shipment.

To set up the box, raise the body thereof, and bend up the partitions 23. The eggs, or 80 other articles may now be inserted by pressing down the tongues 20 and 21. After the cells are filled, the end walls 16 of the box are bent up and secured, as described, and the lid 14 is swung closed and fastened. 85 After emptying the box, it can again be folded flat.

I claim:

A foldable box comprising a bottom, side walls, a perforated top, and a lid foldable 90 over said top, said parts being formed out of a single blank, and the ends of the bottom having integral flaps provided with slits adjacent to their free ends, said flaps being bendable upward to form the end 95 walls of the box, and the slits coinciding with the aforesaid perforated top when the flaps are thus bent, the ends of said top hav-

ing tongues passing through the slits and projecting therefrom, said projecting portions of the tongues and the material of the flaps above the slits being foldable over on the top of the box, and the lid of the box being foldable over the last-mentioned folded parts.

In testimony whereof I affix my signature in presence of two witnesses.

ANNA L. PECK.
